To all whom it may concern:

Be it known that I, DAVID H. Fig. 5 is a similar view of the other end edge of the case.

The body of the case is adapted to contain powder, rouge or other materials, and a hinged door normally closes an opening in the top of the case and is flush therewith, as clearly shown in Fig. 1 of the drawing.

I claim:

The ornamental design for a vanity case or analogous article, as shown and described.
